WALDEMAR HESSLING, OF LONDON, ENGLAND, ASSIGNOR TO STURTEVANT ENGINEERING COMPANY, LIMITED, OF LONDON, ENGLAND.

CENTRIFUGAL FAN OR PUMP.

1,062,006.

Specification of Letters Patent.

Patented May 20, 1913.

Application filed August 25, 1911. Serial No. 645,970.

To all whom it may concern:

Be it known that I, WALDEMAR HESSLING, a citizen of the United States, residing at London, England, have invented certain new and useful Improvements in Centrifugal Fans or Pumps; and I do hereby declare the following to be a full, clear, and exact description of the invention, such as will enable others skilled in the art to which it 10 appertains to make and use the same.

This invention has reference to the class or type of rotary fans and pumps in which the fluid operated on is drawn in centrally and discharged centrifugally and the object of my invention is to obviate certain defects inherent in such fans as heretofore made as will be hereinafter made clear.

Such fans or pumps usually consist of a multi-bladed drum rotated by a central 20 shaft the fluid being admitted at one side into the drum in an axial direction and discharged therefrom circumferentially. Such drums are rotated at a fairly high speed and a matter of considerable importance is 25 that the free and natural movement of the fluid from within the drum to the blades constituting said drum be not interfered with or obstructed as otherwise a loss of efficiency for a given speed of rotation as 30 well as for a given expenditure of power results.

Another matter of considerable importance is that the rotating parts shall be constructed and supported so as to be well and 35 properly balanced, as otherwise a limit to the speed of rotation at which the parts may safely be run is soon reached, this necessitating the employment of a larger fan or pump for a given result than would be necessary if the parts were properly balanced.

Heretofore the drums of such fans or pumps have been usually supported in one of two ways, each of which possesses advantages as well as disadvantages compared 45 with the other.

One way is to support the drum by arms or spokes springing from a boss fixed on the driving shaft and connected to the drum at points in a plane located centrally—lengthwise—of said drum. The other way is to connect the drum (or the blades constituting the drum) at one end to a disk mounted on the driving shaft.

By the former or "arm" method of support the rotating parts are well balanced 55 and may with safety be run at a very high speed but with arms as heretofore made, such fans do not give the efficiency to be attained by the second or "disk" method. The reason of this decreased efficiency is 60 due to the fact (as will be made clear hereinafter) that the arms as heretofore made interfere seriously with the free and natural movement of the fluid from within the drum to the blades. This defect is avoided when 65 a drum is carried at one end by a disk or equivalent, but by reason of such one-sided supporting of the drum the proper balance of the rotating parts is not attained and it is known that such drums, even when ro- 70 tated at no higher speed than that for which they were designed and constructed, have become distorted or deformed and have even been known to "burst" notwithstanding 75 that the free or open end of the drum is provided with a ring or annulus. This tendency to deformation and consequent risk of bursting has been recognized by fan makers, and to overcome the difficulty, the free or open end of the drum has been connected by 80 tie-rods to a boss or disk on the driving shaft, but as these rods pass angularly across the space within the drum, their employ- 85 ment imports the defect inherent in the "arm supported" drum, already referred to, in that said rods seriously interfere with the free and natural passage of the fluid from within the drum to the blades. Fur- 90 ther, the drums (whether supported centrally by arms or on one side by a disk) have also been provided with plates or 95 blades projecting into the space inclosed by the fan blades, to add stiffness and rigidity thereto, but as heretofore made such plates have most seriously interfered with the free and natural movement of the fluid from within the drum to the fan blades.

My invention consists in a fan or pump of the type referred to and having strength- 100 ening plates or blades extending into the space inclosed by the fan or pump blades in which the strengthening or stiffening plates are shaped in the direction of rotation to a curve which is coincident with the natural path of movement of the fluid relatively to 105 the rotating fan or pump blades during its

movement from the interior to the inner periphery of the drum constituted by the blades.

Another feature of my invention consists 5 in supporting the drum by one or more sets of arms which are made, or portions of which are made to a curve similar to that referred to with respect to the plates.

In the accompanying drawings, Figure 1 10 shows in diagrammatic sectional view, transverse to the axis, a portion of a drum embodying my invention; Fig. 2 is a longitudinal sectional view of a drum in a casing, the upper portion of the drum being shown 15 as supported by a single set of arms, while the lower portion is shown as supported upon double arms; and Fig. 3 is a transverse sectional view of the drum apart from the casing.

20 In the illustrated embodiment of the present invention shown in the drawings, the drum A comprises the rings A¹, to which the ends of the blades B are secured. The drum is mounted upon and rotated by the 5 shaft C by means of the supporting arms D, which are arranged in a single plane or in pairs, as shown in Fig. 2. These arms are attached to the strengthening or stiffening plates E, which project inwardly beyond the 0 inner periphery of the blades B. Preferably the drum is mounted in a snail-shaped casing F, as is the general practice with this type of fan. Although this casing is shown 35 with a single intake opening on one side thereof, it is obvious that the drum is equally well adapted for use with a casing having an inlet opening on each side thereof.

When the drum is rotated, the fluid will 40 flow radially toward the inner periphery a of the drum, as indicated by the broken lines a¹, (see Fig. 1); but while the fluid is so moving, the blades B will be constantly moving at right angles thereto and in a circular path, so that relatively to the moving 45 blades B the fluid is moving in a path which is indicated by broken lines b¹ and which is found to be a true logarithmic spiral if the acceleration of speed at which the fluid travels from the center of the drum to the 50 blades be constant.

If the acceleration referred to be not constant, then the curve constituting the path of movement of the fluid relatively to the blades will be different although generally 55 resembling a logarithmic spiral; but in any case, the exact curve can be found when once the speed at different points of the radial movement of the fluid (which can be determined) as well as the rotative speed of 60 the blades be known. It is to this curve that I make the arms D and plates E.

65 It will be seen from the diagram that if the support-arms and the inwardly extending plates were made radial, they would constantly cross the natural path (b¹) of

movement of the fluid from the interior to the inner periphery of the drum, and this is instrumental in setting up resistance which on account of the high speed at which the drum is rotated is sufficient to very appreciably reduce the efficiency of the fan or pump for a given expenditure of power.

If the arms and plates be made curved, such loss in efficiency will occur unless the 70 form of curve be that hereinbefore indicated and the nearer to that curve that the shape of the arms and plates approaches, the less 75 will be the loss in efficiency.

Each of the plates E is made to extend to the outer periphery d of the drum and the 80 portion situated between and connected to the rings A¹ is shaped to act as one of the fan or pump blades. It must here be observed that although the fan pump blades 85 B are inclosed at their ends by rings A¹, the plates E (except the parts referred to which serve as fan or pump blades and are located between the rings A¹) are not inclosed or provided with any shrouding. This is essential, as otherwise the volumetric 90 efficiency of the fan or pump is very greatly reduced owing to the obstruction of the fluid in its movement axially into the drum.

Owing to the greatly reduced linear speed 95 of the arms near their axis of rotation as compared with that at or near the periphery of the drum, comparatively slight resistance only is set up if the arms near to their juncture with the boss carrying them cut across the path of movement of the fluid; and it 100 may be advantageous for obtaining greater strength to make the arms radial near the center of the drum about as shown in Fig. 3. My invention is not therefore limited to arms, the whole of which are made curved 105 as described. As the plates E are made of a width corresponding substantially to the length of the drum, these should be made for their full depth to have the shape described.

While I have shown in the accompanying 110 drawings, and described in the foregoing specification what is now considered a preferred embodiment of my invention and the several features thereof, my invention, except where so specifically defined in the 115 claims is not limited to such illustrated embodiment, but may be embodied in other constructions containing only one or more of said features, and differing in form and arrangement of parts from that above shown 120 and described.

Having thus described my invention, what I claim is:—

1. In a centrifugal fan or pump, the combination with a plurality of blades arranged 125 in substantially drum form, of a plurality of strengthening plates projecting inwardly beyond the inner edges of the blades, the inwardly projecting portion of the plates being shaped in the direction of their rotation 130

to a curve conforming substantially to a logarithmic spiral with the advancing face of such portion convex and means for supporting the blades and plates, substantially as described.

2. In a centrifugal fan or pump, the combination with a plurality of blades arranged in substantially drum form, of a plurality of strengthening plates projecting inwardly beyond the inner edges of the blades, the inwardly projecting portion of the plates being shaped in the direction of their rotation to a curve conforming substantially to a logarithmic spiral with the advancing face of such portion convex and supporting arms attached to and corresponding in curvature with the plates, substantially as described.

3. In a centrifugal fan or pump, the combination with a plurality of blades arranged in substantially drum form, certain of said blades projecting inwardly beyond the inner edges of the other blades, the inwardly projecting portions of said blades being shaped in the direction of their rotation to a curve conforming substantially to a logarithmic spiral with the advancing faces of such projections convex, of supporting arms attached to said inwardly projecting blades, substantially as described.

4. In a centrifugal fan or pump, the combination with a plurality of blades arranged in substantially drum form, of a plurality

of supporting arms shaped in the direction of their rotation to a curve conforming substantially to a logarithmic spiral with the advancing faces of the arms convex, substantially as described.

5. In a centrifugal fan or pump, the combination with a plurality of blades arranged in substantially drum form, the advancing faces of the blades being concave, certain of said blades projecting inwardly beyond the inner edges of the other blades, the inwardly projecting portions of said blades having their advancing faces convex and shaped in the direction of their rotation to a curve conforming substantially to a logarithmic spiral, and means for supporting the blades, substantially as described.

6. In a centrifugal fan or pump, the combination with a plurality of blades arranged in substantially drum form, the advancing faces of the blades being concave, certain of the blades being formed with portions projecting inwardly beyond the inner portion of the other blades to form strengthening plates, the inwardly projecting portions of said blades having their advancing faces convex, and means for supporting the blades and plates, substantially as described.

WALDEMAR HESSLING.
